UNITED STATES PATENT OFFICE

CHARLES D. BLACKMON, OF ROCHESTER, NEW YORK, ASSIGNOR TO SMITH JUNIOR CO., INC., OF ROCHESTER, NEW YORK, A CORPORATION OF NEW YORK

DESIGN FOR A LIQUID-DISPENSING APPARATUS

Application filed May 8, 1930. Serial No. 35,541. Term of patent 14 years.

To all whom it may concern:

Be it known that I, CHARLES D. BLACKMON, a citizen of the United States, residing at Rochester, in the county of Monroe and State of New York, have invented a new, original, and ornamental Design for a Liquid-Dispensing Apparatus, of which the following is a specification, reference being had to the accompanying drawing, forming part thereof.

In the drawings:

Fig. 1 is a top view of a liquid dispensing apparatus showing my new design; and

Fig. 2 is a front view in elevation thereof.

I claim:

The ornamental design for a liquid dispensing apparatus, as shown.

CHAS. D. BLACKMON.
